(57) **CLAIM**

The ornamental design for a multi-surface vacuum cleaner, as shown and described.

DESCRIPTION

FIG. 1 is a front perspective view of a multi-surface vacuum cleaner showing our new design;

FIG. 2 is a front view thereof;

FIG. 3 is a left side view thereof, the right side being a mirror image;

FIG. 4 is an enlarged top view of the multi-surface vacuum cleaner;

FIG. 5 is an enlarged view of the multi-surface vacuum cleaner shown within the area designated as 5 in FIG. 1;

FIG. 6 is an enlarged view of the multi-surface vacuum cleaner shown within the area designated as 6 in FIG. 2; and,

FIG. 7 is an enlarged view of the multi-surface vacuum cleaner shown within the area designated as 3 in FIG. 3.

The details of the multi-surface vacuum cleaner shown in broken lines form no part of the claimed design. The oblique shade lines in FIGS. 1, 2, 4, 5, and 6 show transparency or translucency. The dot-dashed broken line in FIGS. 5-7 show a boundary of the enlarged view and forms no part of the claimed design.
